Timothy A. Curtis

United States Patent Office.

TIMOTHY A. CURTIS, OF BROOKFIELD, MASSACHUSETTS.

Letters Patent No. 62,015, dated February 12, 1867.

IMPROVED SOLE-CUTTING MACHINE.

The Schedule referred to in these Letters Patent and making part of the same.

TO ALL WHOM IT MAY CONCERN:

Be it known that I, TIMOTHY A. CURTIS, of Brookfield, in Worcester county, State of Massachusetts, have invented a new and useful Improved Sole-Cutting Machine; and I do hereby declare the following description and accompanying drawings are sufficient to enable any person skilled in the art or science to which it most nearly appertains to make and use my said invention or improvements without further invention or experiment.

In the present system of manufacturing boots and shoes, the advantages of shifting the knife used in cutting the soles, so as to cut them "toe and heel" alternately, are too obvious to need a particular description; and to do this with facility and enable the operator to tend the machine in rapid operation are the objects of my improvements. To these ends their nature consists in securing the knife to a movable holder, turning on a support and having suitable means to swing it half round between each cut, and placing it in a frame, to which, also, is attached a lifting-bed, operated by levers or other suitable means, to force it against the knife. In the accompanying drawings—

Figure 1 is a side view of my improved sole-cutter.

Figure 2 shows a section of the knife-holder and its support on a plane parallel to fig. 1.

Figure 3 shows some variations hereinafter to be described.

The same letters indicate the same parts in each.

A A is the frame; B the knife-holder, supported by the plate C and operated by the catch-ring D, which has teeth meshing in the rack E; F is a connecting-rod from the rack E to the lever G; H is a stop catch-pin to hold B in position during the cut; I is the cutting-block, held in the adjusting-box J, forming part of the table K, which is supported on the standard L with its elevating screw M and nut N, and is raised by means of the levers O P, the latter forming a treadle and having an extension, P', to which is attached the weight Q to give force to the stroke. R is a spring to assist in raising the treadle. The lever G turns on a stud at S, and has an arm and connection, T, to P', by which it is operated. V V' are adjusting screws to set the block I to the edge of the knife.

In operation the leather is placed on the block I, and the workman treading on the lever P forces up the block against the knife in the holder B, which has a bearing at each end at x x', on the frame A A, to give it solidity. The lever P being thrown forward carries the weight Q, whose momentum gives sufficient force or blow to the stroke; the connection T, lever and connection F, give motion to the rack E, which turns the ring D half round, and a projection from the rack hitting the lever U at the last part of its motion raises the stop-pin H, so that on the return of the treadle to position the ring D, by a catch on its under surface, catching on a notch on B, carries it with it half round, and the pin H, dropping into a place made for it, retains it until again released by the next cut.

I am aware that the swinging the knife half round between each cut is an old device, and also that knives have been attached to reciprocating shafts in various positions. Mine, it will be seen, differs from all these in turning on an internal support and in receiving the stroke on solid bearings at each end of the knife-holder, and raising the work up to the knife.

It is evident that for the various kinds of soles used some variations may be desirable; one is shown at fig. 3 as suitable for some kinds, and other variations of construction will readily suggest themselves in applying my invention to the various circumstances attending the kind of work desired to do, as I do not claim the precise form or construction.

But what I claim as new, and desire to secure by Letters Patent, is—

1. I claim supporting the knife-holder B on an internal support, in connection with the solid bearings of the holder on the frame at x' x, when the knife is swung half round between each cut by means of the levers, rack, and catch-ring, or their equivalents, substantially as set forth.

2. I claim raising the block and table, in connection with the swinging-knife, in the manner and for the purposes substantially as above described.

TIMOTHY A. CURTIS.
